(57) **CLAIM**

The ornamental design for a digital scale, as shown and described.

DESCRIPTION

FIG. 1 is a front perspective view of a digital scale in accordance with an embodiment;

FIG. 2 is a front view thereof;

FIG. 3 is a back view thereof;

FIG. 4 is a top plan view thereof;

FIG. 5 is a bottom plan view thereof;

FIG. 6 is a side view thereof;

FIG. 7 is an opposite side view thereof;

FIG. 8 is a back view in accordance with a first alternative embodiment;

FIG. 9 is a top plan view of the first alternative embodiment;

FIG. 10 is a bottom plan view of the first alternative embodiment;

FIG. 11 is a side view of the first alternative embodiment;

FIG. 12 is an opposite side view of the first alternative embodiment;

FIG. 13 is a back view in accordance with a second alternative embodiment;

FIG. 14 is a top plan view of the second alternative embodiment;

FIG. 15 is a bottom plan view of the second alternative embodiment;

FIG. 16 is a side view of the second alternative embodiment;

FIG. 17 is an opposite side view of the second alternative embodiment;

FIG. 18 is a back view in accordance with a third alternative embodiment;

FIG. 19 is a top plan view of the third alternative embodiment;

FIG. 20 is a bottom plan view of the third alternative embodiment;

FIG. 21 is a side view of the third alternative embodiment;

and,

FIG. 22 is an opposite side view of the third alternative embodiment.

The broken line showing of structural features is included for the purpose of illustrating non-claimed subject matter and forms no part of the claimed design.
